(57) **CLAIM**

The ornamental design for a vehicle wheel, as shown and described.

DESCRIPTION

FIG. 1 is a front elevation view of a vehicle wheel;
FIG. 2 is a perspective view of the vehicle wheel; and,
FIG. 3 is a left side elevation view of the vehicle wheel.
In the drawings the broken lines depict portions of the wheel
that form no part of the claimed design.**1 Claim, 3 Drawing Sheets**FIG. 1

FIG. 2

FIG. 3
